UNITED STATES PATENT OFFICE.

WILLIAM ARTHUR COLLINGS, OF KANSAS CITY, MISSOURI.

SAFETY-BLADE KNIFE.

1,228,409.

Specification of Letters Patent.

Patented June 5, 1917.

Application filed September 10, 1915. Serial No. 49,969.

To all whom it may concern:

Be it known that I, WILLIAM A. COLLINGS, a citizen of the United States, and a resident of Kansas City, in the county of Jackson and State of Missouri, have invented certain new and useful Improvements in Safety-Blade Knives; and I do hereby declare that the following is a full, clear, and exact description of the same, 10 reference being had to the accompanying drawings, and to the numerals of reference marked thereon, which form a part of this specification.

There are many different kinds of safety razors in use, in which detachable double edged safety blades are used, of a type similar to the "Gillette" safety razor blades. These blades are, of course, adaptable for shaving purposes for a limited length of 20 time only, after which the blades are discarded as useless, resulting in the waste and destruction of material that might be reused to advantage.

This invention relates to a safety blade 25 knife, consisting of few parts and adapted to receive detachably mounted therein used safety razor blades after the same have served their purpose, and are no longer adapted for use in shaving, thus making it 30 possible to utilize the blades for cutting, paring and other purposes.

It is an object of this invention to construct a knife handle adapted to receive a safety razor blade mounted therein.

35 It is also an object of this invention to construct a knife, to receive a safety razor blade for use therein, and which affords a shield or covering therefor when the knife is not in use.

40 It is furthermore an object of this invention to construct a folding knife handle adapted to receive releasably mounted therein, discarded safety razor blades, in such a manner that the same may be used for 45 cutting or paring purposes, similar to a regular knife.

It is finally an object of this invention to construct a knife handle for the utilization of used safety razor blades, durable in construction and simple in operation.

The invention (in a preferred form) is illustrated in the drawings and hereinafter more fully described.

In the drawings:

55 Figure 1 is a conventional side elevation

of a device embodying the principles of my invention shown in closed position.

Fig. 2 is a section taken on line 2—2, of Fig. 1.

Fig. 3 is a horizontal section view taken 63 through the device when in open position, showing parts in elevation.

Fig. 4 is a section taken on line 4—4, of Fig. 3, showing the complete side view.

As shown in the drawings:

The device consists of a handle 1, composed preferably of metal, although other material suitable for the purpose may be used; said handle 1, having inwardly stamped indentations forming circular knobs or 70 projections 2, formed near one end thereof, and as clearly shown in Fig. 4, also provided with an outturned flange 3 extending around three sides of the knob section of said handle. Detachably mounted on said 75 handle 1, is an apertured "Gillette" or other safety razor blade 4, the apertures thereof engaging over said projections 2, to hold the blade secure. To positively retain said blade 4, in position and prevent the same 80 becoming disengaged from the indentations 2, a plate 5, is slidably fitted within said flange 3, and frictionally held therein. One edge of said blade 4, projects above the upper margin of said handle 1, and said plate 5, to 85 afford a cutting edge. Pivotedly mounted on said handle 1, by means of a rivet 6, or other suitable means is a guard handle 7, of U-section, having an integral hood or guard 8, also of U-section, formed thereon. 90 Said guard handle 7, and hood 8, are open at their ends and along one side, to permit the same to close over said handle 1, to inclose and protect the blade 4, when not in use.

95 The operation is as follows:

The operation of the device is simple and with the knife open as shown in Fig. 4, the blade 4, may be removed and replaced by simply sliding the plate 5, out of engagement with the flange 3.

I am aware that various details of construction may be varied through a wide range without departing from the principles of this invention, and I therefore do 105 not purpose limiting the patent granted otherwise than necessitated by the prior art.

I claim as my invention:

1. In a device of the class described, a handle, a razor blade, interfitting elements 110

2
on said handle and blade for uniting the two, a plate, a flange on three sides of said handle for slidably receiving said plate to hold said blade in position, and a cover guard pivotally mounted on the other end of said handle and adapted to fold over and cover the same.

2. In a device of the class described, a handle, projections integrally formed thereon and adapted for engagement with a safety razor blade, a plate, a flange on three sides of said handle for slidably receiving

said plate to hold said blade in position, and a cover guard pivotally mounted on the other end of said handle and adapted to fold over and cover the same.

In testimony whereof I have hereunto subscribed by name in the presence of two subscribing witnesses.

WILLIAM ARTHUR COLLINGS.
